UNITED STATES PATENT OFFICE

CHARLES H. LEONARD, OF GRAND RAPIDS, MICHIGAN.

DESIGN FOR A GAME-BOARD.

SPECIFICATION forming part of Design No. 27,732, dated October 12, 1897.

Application filed August 18, 1897. Serial No. 648,728. Term of patent 7 years.

To all whom it may concern:

Be it known that I, CHARLES H. LEONARD, a citizen of the United States, residing at Grand Rapids, in the county of Kent and State of Michigan, have invented a certain new and original Design for Game-Boards, of which the following is a specification.

This design relates to boards upon which games are played, and the distinctive features thereof are the irregular elevations and depressions and the serpentine groove on the surface of said board, as more fully illustrated in the accompanying drawings, in which—

Figure 1 is a plan view of a game-board embodying my invention, and Fig. 2 a longitudinal section on the line 2 2 of Fig. 1.

Like letters refer to like parts in both of the figures.

A represents a board of any desirable dimensions having a smooth under surface and inclosed by the sides B, which project above the upper surface of said board and are se-

cured to the edges thereof. The upper surface of said board A is made uneven to represent a golf-field, the irregular protuberances C representing hills or knolls, and the serpentine groove D represents a creek.

E E are hemispherical depressions in the surface of said board, and F F are small plates secured to the surface of said board near each depression.

G is a plate secured to the surface of said board and represents the starting T of a golf-field.

Having thus fully described my invention, what I claim is—

The design for a game-board, substantially as shown and described.

In testimony whereof I affix my signature in presence of two witnesses.

CHARLES H. LEONARD.
